UNITED STATES PATENT OFFICE.

WILLIAM R. WOOD AND SAMUEL BARR, OF BUTLER, IOWA.

MACHINE FOR BORING AXLE-HOLES IN HUBS, &c.

SPECIFICATION forming part of Letters Patent No. 259,447, dated June 13, 1882.

Application filed August 30, 1881. (No model.)

To all whom it may concern:

Be it known that we, WILLIAM R. WOOD and SAMUEL BARR, citizens of the United States, and residing at Butler, in the county of Scott 5 and State of Iowa, have invented a new and useful machine for boring axle-holes in hubs and other borings requiring irregular and varying diameter, of which the following is a specification as applied to boxing and cham- 10 bering wheel-hubs.

Our invention relates to machinery for boxing and chambering wheel-hubs, wherein the required form of the hole sought is obtained by the inherent form of the shaft employed, 15 which passes through fixedly-centered but flexible bearings.

The object of the invention is to provide a direct means for boring a hole the longitudinal lines of which may be convergent, divergent, 20 convex, concave, or corrugated, owing to the shape of the form-rod used as a part of the shaft. In this instance we illustrate a hole the longitudinal lines of which represent to each other, first, a section parallel; second, a 25 section concavo-convergent; lastly, a section increasingly convergent. The parallel walls of the hole are formed while the bearings are in line with the axis of the threaded feed-shaft around which at this point the bit performs its 30 revolutions. The arch and slight taper in the mid-section are due to the curve in the form-rod. The final increased taper is due to the deflected part of the form-rod gradually drawing the line of cut inward by constantly nar- 35 rowing revolutions until the final circles of the bit are performed around the axis of the form-rod, while the feed-shaft is now operating at a slight angle through its flexible bearing. To prevent binding of the form-rod as it passes 40 its bearing, we find it sufficient in practice to somewhat flatten the deflected part, so that its oblique diameter will fill the countersunk guide or bearing when the angle is presented.

Our invention further relates to a combination of devices designed and adapted to instantly grip and center the work; also devices which allow ready means of introducing, operating, or withdrawing the shaft.

Figure 1 of the accompanying drawings represents a perspective view of our machine. Fig. 2 is a view of the operating-shaft in a lon-

itudinal section of hub. Fig. 3 is a top view of one of the clutches, showing the devices for holding the feed-shaft. Fig. 4 is an under view of the same, showing the mechanism for centering the clutch. Fig. 5 is a cross-section of the offset-knuckle *l*.

Similar letters refer to similar parts throughout the several views.

A is the operating-shaft. *A* is the threaded feed-shaft. *i* is the form-rod. *l* is a rigid offset-knuckle, supplied with a cutting-bit, *s*. *g* is a set-screw to allow the adjustment of the bit to different sizes. *E* is a hand-crank for rotating the shaft, which may be replaced by any convenient power.

The inner lines of the section of hub *x x*, Fig. 2, substantially represent the lines of cut when a form-rod of the given shape is used.

The further and prime use of the offset *l* is to lead the circle of bit *s* on a deflection of the form-rod *i* from the axis of *A* to the axis of *i* at *l*. (See Fig. 6, which is a cross-section of the offset-knuckle *l*.)

The dotted line *M* around *A* represents the first circles of the bit *s* around the shaft *A*.

The dotted line *N* around *i* represents the final circle of bit *s* around the form-rod *i* at *l* after traversing the deflection of *i*, which throws *N*, with all the intermediate variations, concentric with *M*, the effect of which is seen in *x x*, Fig. 2.

If it is desired to box to the dotted lines *v v*, Fig. 2, it is only necessary to set the bit out the required depth and repeat the proper distance.

The open centered disk *m* is the frame-work of the clutch *H*, and may consist of a three-armed cross-tree bearing three pairs of jaws, *n n*, and used for the purpose of holding in place the grip-pins *P P* and rim *O*, hereinafter more fully described.

A section of the edge of the disk *m* is provided with cogs to be operated on by the lock *k*, attached to *O*.

Fig. 3 illustrates the mechanism for holding the shaft *A i* centrally in the clutch and governing the feed, also allowing the necessary flexibility.

b b is a hinged collar, supplied with wooden followers *w w*, so arranged that they may be driven inward to compensate for wear, if found

necessary, being cut with thread to fit the feed-shaft A when closed around it, as seen in Fig. 1, and held by the link y centrally and securely against the post t under the guard u.

5 Fig. 3 also shows the open center of the disk m, allowing the ready introduction or withdrawal of the shaft A i when the collar b b is thrown open.

Fig. 4 is a view of the under side of clutch 10 H, the use of which is to grip the hub centrally and securely. n n are jaws, being part of disk or cross-tree m, hereinbefore referred to.

O is a loose rim in place between the jaws n n, and having cut through it three several 15 eccentric slots used to draw the square grip-pins P P, which are provided with lips to fit the slots in the rim O, and are moved radially and simultaneously across the rim and through the jaws n n, each alike by the same pitch of 20 the slots, as the rim is partly turned right or left by the handle e. k of Fig. 3 is a lock provided with a lever-handle, and having cogs, it being hung eccentrically that it may be thrown out of gear, the use of which is to the more

securely tighten and lock the rim O by means 25 of the cogs meshing and drawing on the cogs of a section of m. The clutch D is substantially the same as H in regard to the gripping movement.

What we claim as our invention, and desire 30 to secure by Letters Patent, is—

1. In a machine for enlarging tubular borings, a guide-plate operating on a form-rod and feed-shaft, having a cutting-tool attached thereto, substantially as described, in combination with mechanism, substantially as described, for actuating the shaft and mechanism.

2. In combination with the feeding-shaft, the collars b b, having the followers w w, of wood, the latter being capable of adjustment 40 to compensate for wear, substantially as described.

WILLIAM R. WOOD.
SAMUEL BARR.
